CLAIM

The ornamental design for a pontoon boat with elevated front wave deflector panel, as shown and described.

DESCRIPTION

FIG. 1 is an upper isometric view of a pontoon boat with a front wave deflector panel.

FIG. 2 is a lower isometric view of the pontoon boat with a front wave deflector panel of FIG. 1.

FIG. 3 is a top side view of the pontoon boat with a front wave deflector panel of FIG. 1.

FIG. 4 is a bottom side view of the pontoon boat with a front wave deflector panel of FIG. 1.

FIG. 5 is a left side view of the pontoon boat with a front wave deflector panel of FIG. 1.

FIG. 6 is a right side view of the pontoon boat with a front wave deflector panel of FIG. 1.

FIG. 7 is a front side view of the pontoon boat with a front wave deflector panel of FIG. 1.

FIG. 8 is a rear side view of the pontoon boat with a front wave deflector panel of FIG. 1.

FIG. 9 is an upper isometric view of another pontoon boat with a front wave deflector panel.

FIG. 10 is a lower isometric view of the pontoon boat with a front wave deflector panel of FIG. 9.

FIG. 11 is a top side view of the pontoon boat with a front wave deflector panel of FIG. 9.

FIG. 12 is a bottom side view of the pontoon boat with a front wave deflector panel of FIG. 9.

FIG. 13 is a left side view of the pontoon boat with a front wave deflector panel of FIG. 9.

FIG. 14 is a right side view of the pontoon boat with a front wave deflector panel of FIG. 9.

FIG. 15 is a front side view of the pontoon boat with a front wave deflector panel of FIG. 9; and,

FIG. 16 is a rear side view of the pontoon boat with a front wave deflector panel of FIG. 9.

The broken lines shown in the drawings are included for the purpose of illustrating unclaimed portions of the pontoon boat with elevated front wave deflector panel and form no part of the claimed design. The dot-dash lines shown in the drawings are included for the purpose of illustrating boundaries between claimed and unclaimed portions of the pontoon boat and form no part of the claimed design.
